(57) **CLAIM**

The ornamental design for an outdoor dial controller, as shown and described.

DESCRIPTION

FIG. 1 is a front elevation of an outdoor dial controller showing our new design;

FIG. 2 is a left side elevation of the controller of FIG. 1;

FIG. 3 is a rear elevation of the controller of FIG. 1;

FIG. 4 is a right side elevation of the controller of FIG. 1;

FIG. 5 is a top plan view of the controller of FIG. 1;

FIG. 6 is a perspective view of the controller of FIG. 1 in a partially opened configuration; and,

FIG. 7 is a front view of the controller of FIG. 1 in a substantially opened configuration.
